(57) **CLAIM**

The ornamental design for a beverage container, as shown and described.

DESCRIPTION

FIG. 1 is a top rear perspective view of a beverage container according to the novel design.

FIG. 2 is a bottom front perspective view of a beverage container according to the novel design.

FIG. 3 is a top plan view of a beverage container according to the novel design.

FIG. 4 is a front elevational view of a beverage container according to the novel design.

FIG. 5 is a rear elevational view of a beverage container according to the novel design; and,
FIG. 6 is a bottom plan view of a beverage container according to the novel design.

The broken lines included in the drawings depict elements that are not part of the claimed design.
